UNITED STATES PATENT OFFICE.

BEN KING FORD, OF DETROIT, MICHIGAN, ASSIGNOR TO DETROIT CAN COMPANY, OF DETROIT, MICHIGAN, A CORPORATION OF NEW JERSEY.

CONTAINER.

1,203,866.

Specification of Letters Patent.

Patented Nov. 7, 1916.

Application filed March 20, 1913. Serial No. 755,580.

To all whom it may concern:

Be it known that I, BEN KING FORD, a citizen of the United States, residing in Detroit, in the county of Wayne and State of Michigan, have invented a new and useful improvement in Containers, of which the following is a specification.

This invention relates to an improvement in containers and it consists in the novel devices and combination of parts and devices hereinafter set forth and made the subject matter of claim.

In the accompanying drawing which forms a part of this specification, Figure 1 is a perspective view of the improved container; Fig. 2 a vertical cross section of the same taken on the line 2—2 of Fig. 1; Fig. 3 a plan view of the container with the sliding cover removed; Fig. 4 a plan view of 20 the sliding cover removed from the container; Fig. 5 a plan view of the sealing cover removed from the container; Fig. 6 a cross section on the line 6—6 of Fig. 4; Fig. 7 a cross section on the line 7—7 of 25 Fig. 3; and Fig. 8 a cross section on the line 8—8 of Fig. 5.

In containers made with walls of paper or fiber and sheet metal ends, it has been considered desirable practice to countersink 30 the ends to form an internal shoulder and to crimp a flange against the yielding paper or fiber to hold said paper or fiber wall firmly between such crimped flange and the internal shoulder, as this results in a durable and tight union between the sheet metal end and the yielding paper or fiber wall. An inconvenience of this otherwise desirable construction is, however, that the surface of the end is necessarily some distance below the upper edge of the completed structure and this, together with the bead formed by the crimping, has made it difficult to employ it where it is desired to use a second or removable cover, as for instance in containers for baking powder or 40 spices. The present improvement overcomes these difficulties in an exceedingly simple and effective manner, enabling a removable cover and even a perforated one 45 to be easily and cheaply applied and also one that has none of the disadvantages of the ordinary slip cover which cannot be effectively employed in this style of container. To accomplish this result I make 50 one of the sheet metal ends with a large

opening preferably suitable for the insertion of a spoon and surrounded by a horizontal shoulder or flange to support a temporary paper or fiber seal piece, and provide a second sheet metal cover, which may 60 be perforated for spice sprinkling, and which I apply as a slide on top of the whole such slide being held in place by inturned edges on two sides engaging the bead formed by the crimping of the sheet metal 65 fixed end to the paper or fiber walls. Such sliding additional end may be easily opened wholly or partially or entirely removed and readily reapplied. This enables the filling of the container through a large opening 70 and the use of a spoon in dispensing its contents when desired, and also the easy removal or placing of the seal piece, and makes it possible to have a perforated 75 sprinkler if that is wanted; and the structure being such that the seal piece may be readily inserted or removed makes the container suitable for a shipping package.

In said drawing, A is the paper wall of the container.

B, B¹ are the sheet metal countersunk heads, the upper head B being perforated by the wide opening B².

C, C are the crimped beads or flanges, between which and the shoulder formed by the countersinking of the ends B, B¹, the walls A are firmly held.

D is a sealing piece of fiber placed over the opening B² to close the same during shipment or whenever it is desired to close 90 the container.

D¹ is the supplemental sliding cover made with the inturned edges D² at two of its sides. This cover may be perforated with the holes d, and may be provided with the stamped up thumb projection d¹. The sliding cover may be applied to the container either by sliding it on endwise or snapping it vertically in place, the latter being the most rapid method and the one which will 100 be usually employed in assembling the parts in manufacture.

The invention is not necessarily limited to containers or cans having a body-portion of paper, but may be combined with body-105 portions of any suitable material.

I claim:

A container having an end of flat-sided form, said end consisting of sheet metal the edges of which are bent to form outstanding 110

flanges which engage and hold the end edges of the body of the container, said end being countersunk within the said flanges to form a space for receiving a removable seal 5 piece and being perforated beneath the seal piece; a sliding cover of sheet metal having opposite straight edges which are bent to embrace the said flanges of the end; and

said separate removable seal piece being confined by said cover in the countersunk portion of the end and sealing the perforation in the end.

BEN KING FORD.
